UNITED STATES PATENT OFFICE.

WILLIAM McLELLAND STEVENSON, OF BENNETTSVILLE, SOUTH CAROLINA, ASSIGNOR
TO SECURITIES HOLDING COMPANY, OF THE STATE OF SOUTH CAROLINA.

ROTARY EXPLOSIVE-ENGINE.

1,001,320.

Specification of Letters Patent. Patented Aug. 22, 1911.

Application filed March 17, 1910. Serial No. 550,042.

To all whom it may concern:

Be it known that I, WILLIAM McLELLAND STEVENSON, a citizen of the United States, and a resident of Bennettsville, in the county of Marlboro and State of South Carolina, have invented certain new and useful Improvements in Rotary Explosive-Engines, of which the following is a specification.

My invention relates to engines of the rotary explosive type, and has for its object the provision of an engine employing an annular casing fixedly secured and divided into a series of casings by slidably mounted radially movable partitions, alternate chambers having explosive chambers communicating therewith, while the remaining chambers comprise the compression chambers and are arranged in communication with the explosive chambers to deliver the compressed mixture thereto.

The driven member of the engine consists of a wheel with projections thereon that extend into the casing aforesaid to form the engine-pistons, the front surfaces of the projections being tangential to the periphery of the wheel, while the rear surfaces are on a plane inclined substantially 45 degrees to the outer surfaces of the projections.

My improved engine will be described in detail hereinafter and illustrated in the accompanying drawings, in which—

Figure 1 is a top plan view, of my improved engine, the casing and rotary member being shown partly in section; Fig. 2, a cross-section of the engine; Fig. 3, a fragmental detail view of the casing, on an enlarged scale, showing the explosive-chamber partly broken away; Fig. 4, a fragmental detail view of the rotary element; Figs. 5 and 6, detail views of one of the slidable partitions and its housing; and Fig. 7, a fragmental sectional view of rotary member and annular casing.

In the drawings similar reference characters indicate corresponding parts throughout the several views.

In the embodiment of my invention shown in the drawings 1 indicates the base of my improved motor, on which is mounted a casing 2, providing the water-jacket and containing an annular casing 3, open toward the interior of the annulus and having its side walls formed with pairs of parallel plates 4, spaced apart.

5 indicates a wheel forming the rotary

element of my improved engine and to which is secured the vertical drive-shaft 6, the outer portion of the wheel having side flanges 7 that fit snugly the spaces between the plates 4 and lugs 8 that extend outwardly from the periphery of the wheel between flanges 7, forming the pistons of the engine.

Lugs 8 have their front surfaces formed tangentially of the periphery of the wheel, while their rear surfaces 10 are inclined at an angle of substantially 45 degrees to the periphery of the wheel and the outer surfaces of the lugs.

Casing 3 is divided into a plurality of 70 chambers by slidable partitions 11, said chambers being even in number, eight being shown in the embodiment of my invention shown in the drawings, and the alternate chambers, indicated at 12, are larger than 75 the intervening chambers 13, chambers 12 constituting the driving chambers and having explosive-chambers 14 secured thereto and communicating with chambers 12 by means of aligned openings 15 in the parallel 80 walls 4. The chambers 13 constitute the compression-chambers and have inlets 16 in their ends nearest the direction from which the wheel 5 rotates, and aligned openings 17 in their opposite ends that are connected 85 with chambers 14 by means of pipes 18, 19 being back-pressure valves in the said pipes 18 to hold the charges compressed in the chambers.

Partitions 11 heretofore referred to are, 90 as stated, slidable, housings 20 being secured to the outer side of the casing 3 to receive the partitions when moved outwardly by the instrumentalities hereinafter described, and said partitions fit said housings air-tight so 95 as to prevent the escape of the explosive mixture from one chamber to the other. Partitions 11 have rods 21 secured to their outer edges and extended through holes 22 in the housings 20, the outer ends of the rods 100 being provided with knobs 23 and 23^a.

24 indicates angular rods slidably mounted on the side of casing 3 and engaging rods 21.

25 designates spaced-apart bearing rollers 105 on rods 24, and 26 a wheel secured to shaft 6 and having a lateral flange 27 extending therefrom that engages rollers 25, said flange being formed with undulations 28, aligned with the lugs 8, to raise and lower the 110

rods as the lugs are passing under the partitions. 29 designates coil-springs mounted on rods 21 and engaging knobs 23^a and the ends of the rods 24 to act as cushions or buffers for the partitions to permit them to give slightly as the lugs pass them.

30 designates exhaust-ports in chambers 12 for the emission of the spent products of combustion.

10 In the engine illustrated in the accompanying drawings four chambers 12 and four chambers 13 are provided and three lugs or pistons 8, so that in operation the three pistons are subjected to four impacts 15 of the exploded gases from the chambers 14 and four compressions are exerted by each piston, the impacts and compressions being divided because of the dissimilar number of impact chambers and lugs, so as

20 to equalize the driving of the rotary element, but it will be apparent that the number of pistons and of impact and compression chambers may be varied, as desired, without altering the spirit of the invention.

25 The flanges 7 by fitting snugly between the plates 4 close the ports 15 and 17 except when openings 31 and 32 come into alignment with them at the proper periods to release the expanded gases from the explosion-chambers 14 or to release the compressed gas from the chambers 13 and permit them to enter the explosion-chambers.

In operation the front surfaces 9 of the pistons 8 enter chambers 13 and compresses 35 the gas therein which, when the ports 17 are alined with the openings 32, passes through the pipe 18 into explosion-chambers 14. At the instant the pistons pass from the compression-chambers 13 to the impact-chambers 12 the charges in the chambers are fired by any suitable mechanism (not shown) and the expanding gas, rushing out of the chambers 14 through ports 15, which are opened by the alinement therewith of 45 the openings 31, impacts with the rear faces of the pistons and drives them forwardly until they pass from the chamber and the spent gas escapes through the exhausts 30, the following piston serving to clear the 50 chamber of the residue while being driven by the next explosion.

As shown and stated above, the impact-chambers 12 are larger than compression-chambers 13, which serves to make the 55 driven stroke longer than the compression stroke, while the inclined faces of the pistons cause the compression and impact strokes to be started gradually, a portion only of the surface being exposed initially 60 and progressively increased.

Having thus described my invention, what I claim is—

1. In a rotary explosive motor, an annular casing having its side walls consisting of spaced-apart parallel plates, sliding partitions suitably mounted and dividing the casing into a series of chambers, alternate chambers being impact-chambers and the intervening chambers compression-chambers, explosion-chambers communicating with 70 said impact and compression chambers through openings in the walls of the casing, a wheel having peripheral flanges extending between the parallel walls of the casing, said flanges having openings therein 75 at intervals to open communication between the explosion-chamber and the chambers in the casing, and pistons extending from said wheel, substantially as shown and described.

2. In a rotary explosive motor, an annular casing having its side walls consisting of spaced-apart parallel plates, sliding partitions suitably mounted and dividing the casing into a series of chambers, alternate chambers being impact-chambers and the intervening chambers compression-chambers, explosion-chambers communicating with said impact and compression chambers through openings in the walls of the casing, a wheel having peripheral flanges extending between the parallel walls of the casing, said flanges having openings therein 80 at intervals to open communication between the explosion-chamber and the chambers in the casing, and pistons extending from said wheel, substantially as shown and described.

3. In a rotary explosive-motor, an annular casing having its side walls consisting of spaced-apart parallel plates, sliding 100 partitions suitably mounted and dividing the casing into a series of chambers, housing for the partitions extending radially of the casing, rods secured to the partitions, rods slidably mounted in the casing and engaging the rods on the partitions, a drive-shaft, a wheel secured to said shaft, an undulating flange on said wheel and engaging said rods to actuate them, another wheel secured to said shaft, and pistons on said wheel and operating in the casing, substantially as 105 shown and described.

In witness whereof, I have hereunto set my hand in presence of two subscribing witnesses.

WILLIAM MCLELLAND STEVENSON.
